CLAIM

The ornamental design for a thin film printer, as shown and described.

DESCRIPTION

FIG. 1 is a front, right, top perspective view of a thin film printer showing my new design;

FIG. 2 is a back, left, bottom perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 2;

FIG. 11 is an enlarged view of the encircled area 11 of FIG. 2;

FIG. 12 is an enlarged view of the encircled area 12 of FIG. 8; and,

FIG. 13 is an enlarged view of the encircled area 13 of FIG. 8.

The short dashed broken lines shown in the drawings depict portions of the thin film printer that form no part of the claimed design. The long dashed broken lines represent the bounds of the enlarged views and form no part of the claimed design.
